UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

PERPETUAL CALENDAR.

1,327,317.

Specification of Letters Patent.

Patented Jan. 6, 1920.

Application filed March 26, 1917. Serial No. 157,351.

To all whom it may concern:

Be it known that I, FRANZ A. FULLER, of the city of Newark, county of Essex, and State of New Jersey, have invented certain new and useful Improvements in Perpetual Calendars, of which the following is a full, clear, and exact description, such as will enable others skilled in the art to which it pertains to make, construct, and use the same, reference being had to the accompanying drawings, and to numerals of reference thereon, forming a part of this specification.

My invention relates to improvements in perpetual calendars, which are adapted to indicate the names of the day of the week, and also the months of the year in chronological order, and has for its objects, to provide a novel device of the character indicated, which shall be simple and effective in construction, comparatively inexpensive in cost, and which, by proper manipulation, will display the name of the day, its date, as well as the name of the month.

My improved calendar is of such form that it is well adapted for advertising purposes, in that the advertisements may be placed or embossed in any suitable manner upon the front thereof. With this end in view, my invention consists in certain novelties of construction and arrangements of parts, as hereinafter set forth and pointed out in the claims. While the preferred form is illustrated in the accompanying drawings, yet it is to be understood that minor changes may be made without departing from the scope thereof.

In the accompanying drawings,

Figure 1 represents a front view of my improved device.

Fig. 2 represents a side elevation of the same, showing the means for holding the device in an upright position.

Fig. 3 represents a front view, with the front plate removed, showing all the parts in their operative position, with the lugs of the front plate in section engaging with the notches of the rear plate.

Fig. 4 represents a front view of the rear plate, showing the bearings and notches for receiving the operative parts, and the front plate.

Fig. 5 represents a sectional side view, taken on lines *a—a* of Fig. 1.

Fig. 6 represents a sectional end view, taken on lines *b—b* of Fig. 1; and 55

Fig. 7 represents a fragmentary sectional view taken on lines *c—c* of Fig. 3, illustrating an integral projection formed on the rear plate, designed to engage with suitable apertures in the apertured dials, to prevent 60 accidental movement thereof.

Similar numerals of reference refer to like parts throughout the specification and drawings.

The improved calendar is preferably made 65 of flexible metal of any kind, such as brass, tin, copper or aluminium, and the parts are of such shape as to lend themselves readily to manufacture by the use of suitable punches and dies, from ordinary sheet 70 metal.

My improved calendar consists essentially of a frame, in which the working parts are contained, the working parts consisting of two disks or dials, preferably of the same 75 diameter, upon one of which are printed the figures 1, 2, 3, 4, 5, 6, 7, 8, 9, 0, and on the other are printed the figures 1, 2, 3, 0, and two apertured dials, preferably of different diameters, upon one of which are printed 80 the days of the week, and upon the other are printed the months of the year, and a spring adapted to be engaged by two disks or dials containing the numerals.

In the drawings, the frame in which said 85 working parts are contained, consists of a front and rear plate, designated by the numerals 1 and 2. The front plate 1 may be made of any suitable material, and with any suitable kind or amount of ornamentation. 90 As shown, it is provided with apertures 3 and 4, designed to expose the number of the day, and an aperture 5, designed to expose the month, said aperture being preferably located below the apertures exposing the 95 number of the day. A suitable recess or cut-out portion 6, is provided at the top of the front plate 1, designed to expose the day.

The front plate 1 is further provided with 100 a marginal flange 7, from which project a plurality of integral ears or lugs 8, the purpose of which will be hereinafter described. The marginal flange 7 is further provided with cut-away portions 9, at the top and 105 sides, for convenience in manipulating the

respective dials and apertured dials, which register with said cut-away portions 9, as shown in the drawings.

- The rear plate 2 is provided along its 5 marginal edges with a plurality of notches 10, corresponding in number to the ears or lugs 8 on the front plate, designed to receive said ears or lugs 8, which are clenched over on the back of the rear plate 2, to secure 10 the front plate 1 to the rear plate 2. The rear plate 2 is provided with a plurality of apertures 11, 11, 11, 12, 12, 13, 13, 13, each aperture surrounded by a circular wall, said circular walls forming integral parts of the 15 rear plate 2, and projecting inwardly from one side of said plate to a height sufficient to form suitable bearings, upon which the disks or dials and apertured dials are rotatably mounted.
- 20 The inner circumferential edge of the apertured dial 14, on which are printed the days of the week, engages with the circular walls of the apertures 11, 11, 11, by means of which the apertured dial 14 is positioned 25 and rotatively mounted upon the rear plate 2. The inner circumferential edge of the apertured dial 15, on which are printed the months of the year, engages with the circular walls of the apertures 13, 13, 13, by 30 means of which the apertured dial 15 is positioned and rotatively mounted upon the rear plate 2.

A flat spring 16, the ends of which are provided with notches 17—17, is positioned 35 and secured upon the rear plate by causing the notches in the ends of the spring to engage with the circular walls surrounding the apertures 12, 12. The dials 18, 18, on which are printed the days of the month, 40 are each provided with a suitable aperture designed to receive the circular walls surrounding the apertures 12, 12, and upon which said dials are rotatively mounted above the ends of the spring 16. The flat 45 spring 16, in close proximity to the notches 17, is provided with projections 19, which are designed to engage with apertures 20 formed in the disks or dials 18, 18, thus preventing the accidental moving of said 50 disks or dials 18.

A lug 21 integrally formed on the front plate 1, and located centrally on said plate, is adapted to enter an aperture 22 located 55 centrally in the rear plate 2, which form means for additionally securing said front and rear plates together, and serve as a means for properly spacing the said front and rear plates.

The rear plate 2 may be provided with an 60 angular extension 23, which may be utilized as a support. The rear plate is further provided with two seats 24, which may be formed on said plate in any desired or convenient manner, the height of which are approximately in line with the top of the apertured

dial 14, on which are printed the days of the week, and which form convenient supports for the apertured dial 15, on which are printed the months of the year. These supports 24 serve to maintain the apertured dial 70 15 in a level position, and further prevent said dial from binding when all of the parts are in their assembled position.

The assembling of my device is very simple and as follows: The apertured dial 75 14 is secured to the rear plate 2 by causing the inner circumferential edge thereof to engage with the circular walls of the apertures 11, 11, 11. The apertured dial 15 is then placed over the dial 14, with its inner 80 circumferential edge engaging the circular walls of the apertures 13, 13, 13. The notched ends 17 of the flat spring 16, are then caused to engage with the circular walls of the apertures 12, 12, whereby said spring 85 is positioned and secured to the rear plate 2. The dials 18, 18 are then mounted on the circular walls of the apertures 12, 12 by means of a central aperture in each dial, the projections 19 formed near each end of the 90 spring engaging with one of the apertures 20 formed in the disks or dials 18, in which manner the dials 18, 18 are secured to the circular walls and spring, to prevent accidental rotation thereof. It will of course be understood that a portion of the periphery of each disk or dial is exposed outside of the marginal edges of the frame. The front plate 1 is then secured to the rear plate 2 by passing the lugs 8 and the lug 21 through the 100 notches 10 and the central aperture 22, and then clenching the same over upon the rear of the rear plate 2.

The back plate 2 may be further provided with stuck-up points 25, designed to engage 105 with suitable apertures 26 formed in the apertured dials 14 and 15, in order to prevent accidental movement of the same.

The operation of my improved calendar is as follows: The parts being in the position 110 shown in Fig. 1 of the drawings, with a portion of the periphery of each disk or dial extending through the cut-away portions 9, the operator's finger engages the exposed periphery of the apertured dial 14 and moves 115 it until the desired day is exposed in the recess 6. The operator then, in the same manner, moves the disks or dials 18, 18 until the desired date is exposed in the apertures 3 and 4. The apertured dial 15 is then moved until the desired month appears in the aperture 5.

Experience has demonstrated that the organization above described is a highly efficient one, and while the device described is 125 the preferred embodiment of my present invention, I do not care to restrict myself to the exact details of constructions, combination and arrangement herein set forth, it being obvious that minor variations thereof, 130

not involving the exercise of invention, may be made by any skilled mechanic, and such departures from what is herein described and claimed, I consider within the 5 scope and terms of my claims.

Having thus described my invention, what I desire to claim and secure by Letters Patent is:—

1. In a calendar, the combination with a 10 frame, comprising a front and a rear plate, said rear plate being provided with integral circular walls extending upwardly therefrom, a pair of day dials, a day-name dial and a month-name dial rotatively secured 15 to the rear plate by means of said integral circular walls, a flat spring, notched at its ends, interposed between said plates, the notched ends thereof bearing against the circular walls upon which said day dials are 20 rotatively secured, said spring further provided with means engaging with apertures in the day dials for preventing accidental movement of said dials.

2. In a calendar, the combination with a 25 frame, consisting of a metallic front and rear plate, the rear plate being provided with integral circular walls struck up and extending upwardly therefrom and notched marginal edges, the front plate provided 30 with integral fastening means registering with the said notched edges of the rear plate for securing the plates together, a pair of day dials, a day-name dial, and a month-name dial interposed between said plates 35 and rotatively located therebetween by means of the integral circular walls of the rear plate, a flat spring, notched at its ends, the notched ends engaging with a pair of the said circular walls whereby said spring 40 is positioned on the rear plate, said spring being further provided with means engaging with apertures in the day dials for preventing accidental movement of said dials.

3. In a calendar, the combination with a 45 frame, consisting of a metallic front and rear plate, the rear plate being provided with integral circular walls struck up and extending upwardly therefrom and notched marginal edges, the front plate provided 50 with integral fastening means registering with the said notched edges of the rear plate for securing the plates together, a pair of day dials, a day name-dial and a month-name dial interposed between said plates 55 and rotatively located therebetween by means of the integral circular walls of the rear plate, a flat spring, notched at its ends, the notched ends engaging with a pair of the said circular walls whereby said spring 60 is positioned on the rear plate, said spring being further provided with means engaging with apertures in the day dials for pre-

venting accidental movement of said dials, and integral means formed on the rear plate 65 engaging with apertures formed on the day-name and month-name dials for preventing accidental movement of said dials.

4. In a calendar, the combination with a frame, consisting of a metallic front and rear plate, the rear plate being provided 70 with integral circular walls struck up and extending upwardly therefrom and notched marginal edges, the front plate provided with integral fastening means registering with the said notched edges of the rear plate 75 for securing the plates together, a pair of day dials, a day name-dial, and a month name-dial interposed between said plates and rotatively located therebetween by means of the integral circular walls of the 80 rear plate, a flat spring, notched at its ends, the notched ends engaging with a pair of the said circular walls whereby said spring is positioned on the rear plate, said spring being further provided with means engaging 85 with apertures in the day dials for preventing accidental movement of said dials, and integral means formed on the rear plate engaging with apertures formed on the day-name and month-name dials for preventing 90 accidental movement of said dials, and supports arranged on the rear plate for the month-name dial to properly space said dial from the day-name dial.

5. In a calendar, the combination with a frame, consisting of a metallic front and rear plate, the rear plate being provided with integral circular walls struck up and extending upwardly therefrom and notched marginal edges, the front plate provided 100 with integral fastening means registering with the said notched edges of the rear plate for securing the plates together, day dials being centrally and rotatively mounted upon a pair of said circular walls of 105 said rear plate and a day-name and a month-name dial being rotatively mounted upon the rear wall and positioned thereon by means of the inner peripheral edges of 110 said dials engaging with some of said circular walls of said rear plate, a flat spring, notched at its ends, the notched ends engaging with a pair of the said circular walls whereby said spring is positioned on the rear plate, said spring being further provided 115 with means engaging with apertures in the day dials for preventing accidental movement of said dials.

This specification signed and witnessed this 24th day of March, 1917.

FRANZ A. FULLER.
